UNITED STATES PATENT OFFICE.

JAMES G. MACLAREN, OF HARRISON, NEW YORK.

PNEUMATIC-DESPATCH-TUBE APPARATUS.

1,366,013.

Specification of Letters Patent. Patented Jan. 18, 1921.

Application filed September 28, 1914, Serial No. 863,793. Renewed November 21, 1916. Serial No. 132,714.

To all whom it may concern:

Be it known that I, JAMES G. MACLAREN, of Harrison, in the county of Westchester and State of New York, have invented certain new and useful Improvements in Pneumatic-Despatch-Tube Apparatus, of which the following is a specification.

This invention relates to carrier systems of the pneumatic type for the transmission of carriers between a central station, and one or more outlying or sub-stations. My invention is more especially concerned with a pneumatic despatch system which is always open to the transmission of carriers regardless of whether other carriers are in transit, and in which system the air current creating means for the propulsion of the carriers is required to operate no longer than is required to deliver a carrier or carriers through the portion of the transit tubes actually in use.

My invention will be best understood by reference to the following description when taken in connection with certain specific illustrative embodiments thereof shown in the accompanying drawings, while its scope will be more particularly pointed out in the appended claims.

In the drawings:

30 Figure 1 is an elevation of one form of carrier transmission apparatus embodying my invention, illustrating a single transit tube connecting a central station with a sub-station;

35 Fig. 2 is a detail view partly in section of a portion of the apparatus, including a carrier, a transit tube and one form of electric circuit controller for causing the maintenance of a previously initiated air current in the apparatus, said controller being shown as it appears when the circuit is closed;

40 Fig. 3 is an enlarged detail view, in section, of the circuit controller as it appears when the circuit is open;

45 Fig. 4 is an elevation of the form which the apparatus takes when there is a plurality of transit tubes for despatching carriers from the central station to the sub-station, and another transit tube for despatching carriers from the sub-stations to the central station;

55 Fig. 5 is a diagrammatic view of the electrical system of the apparatus;

Fig. 6 is an enlarged detail sectional view of the preferred electric circuit controller employed in connection with the form of apparatus shown in Fig. 4;

60 Fig. 7 is an enlarged detail sectional view of a check-valve forming a part of the apparatus shown in Fig. 4; and

65 Figs. 8 and 9 are detail sectional views of electric circuit controllers in the form of manometers connected to the transit tubes employing pressure above that of the atmosphere for the transmission of carriers;

70 Figs. 10 and 11 are detail sectional views of electric circuit controllers in the form of manometers connected to the transit tubes employing pressure below that of the atmosphere for the transmission of carriers; and

75 Fig. 12 is an enlarged detail view in section of a portion of the transit tube and the trip which momentarily closes the motor starting circuit.

Referring to the drawings, and to the specific embodiment of my invention which is illustrated in Figs. 1, 2, 3 and 12, I have there shown a carrier apparatus of the pneumatic type having a transit tube B provided with a despatching inlet A open to the atmosphere at one station and leading therefrom to a discharge station where it is provided with a normally closed valve B⁶. An air current may be created in this transit tube by suitable air current creating means, herein a blower or pump R² suitably connected to the transit tube as by a pipe B³. This blower or pump may be driven by suitable means, herein an electric motor B⁴. The latter is herein connected in circuit with suitable controlling devices for starting the motor into operation to initiate the air current, to maintain the operation of the motor so long as a carrier remains in the system, and to stop the motor when the transit tube is unobstructed. In the present instance, these motor controlling devices include a suitable magnetically operated starting switch B⁵, an appropriate contact maker C to complete a circuit to said switch, and a circuit controller E, the latter being shown in detail in Figs. 2 and 3.

The circuit controller E, as herein shown,

comprises a switch D, whose purpose is to cause the maintenance of the motor circuit previously established by the contact maker C. This circuit controller may be of any suitable construction, and controlled by the differential pressure created by a carrier or carriers in transit. In other words, it may be operated by the changes of pressure in the system due to the presence and absence of carriers. As herein shown, the controller E is provided with a diaphragm chamber E⁴ communicating through a pipe E' with the transit tube B. In this form of my invention, this chamber E⁴ is provided with a flexible diaphragm E³ attached to a spindle E⁵, the latter being suitably connected to operate the switch D.

In the present instance, when there is no carrier in the line and the air pressure on opposite sides of the diaphragm E³ is balanced, the switch D is open as shown in Fig. 3. When, however, owing to the presence of a carrier α in the line, the pressure within the transit tube B and the diaphragm chamber E⁴ becomes reduced to a point below that of the atmosphere, the latter, acting against the diaphragm E³, will cause the latter to operate the switch D to close the circuit and maintain the motor B⁴ in operation as long as a carrier remains in the line. The diaphragm may be provided with suitable means herein a weight E² to restore the diaphragm and switch to their normal position as soon as the pressure on opposite sides of the diaphragm again becomes balanced.

When the apparatus is in normal condition, the pump is at rest and hence atmospheric pressure exists throughout the transit tube, the pipe E' and the chamber E⁴. In other words, the transit tube is normally dead. If now a carrier α be inserted at the despatching inlet A, at the top of the vertical portion of the transit B, the carrier will descend by gravity until it strikes the trip C' of the contact maker C, whereupon the latter will complete a circuit to the magnetically operated switch B⁵, thus causing the latter to complete a circuit to the motor B⁴. The motor, thus started into operation, drives the pump B², and the latter now commences to exhaust air from the pipe B³, the pipe E', the chamber E⁴, and that portion of the transit tube B which is intermediate the carrier α and the outlet valve B⁶.

This exhausting of air will reduce the internal pressure to a point below that of the atmosphere, and since the carrier is exposed on one end to atmospheric pressure, and on the other end to a pressure below that of the atmosphere, the carrier naturally will be propelled toward the discharge station B'. This reduction of pressure within the chamber E⁴ unbalances the equal pressures theretofore existing on opposite sides of the diaphragm E³, and since the atmospheric pres-

sure on the outer face of the diaphragm now predominates over that on its inner face, the diaphragm will at once move inward, thus closing the switch D. This closing of the switch D, following the completion of the motor circuit by the magnetically operated switch B⁵, will keep the motor in operation and thus maintain the previously initiated air current.

The motor will be kept in operation as long as the line remains obstructed by a carrier, and when the latter is delivered through the valve B⁶, since atmospheric pressure can now have free access to the transit tube, the pipe E' and the chamber E⁴, the diaphragm E³ will resume its initial or normal position, thus opening the switch D, and causing the magnet switch B⁵ to become deenergized and to break the motor circuit, thereby stopping the motor and the pump. The transit tube is now again in its normal condition, or "dead." It should be understood, however, that the introduction of the first carrier at the inlet A can be followed by the introduction of successive carriers even though another or other carriers are en route, and that the operation of the pump will continue as long as a carrier remains in the transit tube.

If the transit tube B were extended, as shown by the dotted lines in Fig. 1, past the inlet A to the inlet A', it would be necessary to equip the latter with a contact maker C² similar to the contact maker C, so that the dispatching of a carrier at the inlet A' will energize the magnetically operated starting switch B⁵. The completion of the motor circuit will now start the motor in operation, and its operation will continue until the carrier reaches the vertical riser, whereupon, owing to the action of gravity upon the carrier, the latter in dropping will acquire a velocity greater than that of the air current. This will be followed by a reduction of pressure at the point B⁶, resulting in the stopping of the motor in the manner hereinbefore explained, and the motor will remain at rest until the carrier engages the trip C' of the contact maker C, thus again completing the circuit in the manner already explained.

Referring now to Fig. 4, I have there shown another embodiment of my invention comprising a system of pneumatic dispatch tubes for the dispatch of carriers from sub-stations P, P' and P², to a central station B'. In this form, a transit tube B is provided, at the sub-stations, with inlets G, G' G² and G³, for the introduction of carriers, and a discharge terminal B', the latter being provided with a valve B⁶, through which the carriers will be delivered at the central station.

As a means for dispatching carriers from the central station to the various sub-stations, I have herein provided a series of

transit tubes N. It will be understood that one blower might operate more than one set of transit tubes. The transit tubes N are herein connected by suitable check valves 5 N', having flaps N⁴ and a pipe E⁸ to a chamber E⁹ hereinafter described.

As a means for supplying air under pressure to any one of the transit tubes N at will, I have herein provided a suitable swivel 10 dispatching inlet O, which permits the connection of any one of said tubes to the pressure side or outlet O' of a blower B', as in U. S. Letters Patent to Campbell No. 454,992, issued June 20, 1891. The check valves N' will permit the admission of air under pressure from the particular transit tube N, which is connected with the blower, to the chamber E⁹ of an electric circuit controller (Figs. 4 and 6), but will not permit this air to escape into the two remaining transit tubes N, which are disconnected and open to the atmosphere, as illustrated for example in Fig. 4. Each of the check valves N' is herein provided with a nozzle N² connected by a suitable pipe or rubber tube N⁵ with one of the transit tubes N.

Turning now to the electric system which is the preferred means for the control of the pneumatic system, the pump or blower B² is herein driven by a suitable electric motor B⁴ shown in Fig. 4, and represented diagrammatically in Fig. 5, which is a diagram of the electric system. Referring to Fig. 5, power feeders 10 and 14, indicated as positive and negative, lead from a suitable source of current, not shown. The positive wire 10 has a branch 11 provided with taps 24 leading to terminals at one side of contact makers 1, 2, 3 and 4, located at the terminals G, G' G² and G³, respectively. The branch 11 continues past these contact makers, and is connected to one terminal of a switch D of a suitable circuit controller E. The other terminal of this controller is connected by a wire 12 and taps 25 with the other terminals of the contact makers 1, 2, 3 and 4, respectively.

The wire 12 is continued past the contact makers, and is connected to one terminal of a coil K⁴ of an electro-magnet herein of the solenoid type, the other terminal of which is connected by a wire 13 with the negative wire 14. If, now, the circuit be completed by the closing of any one of the contact makers 1, 2, 3 and 4, or by the switch D, the coil K⁴ will be energized, and when the circuit is broken, said coil will be de-energized.

The electro-magnet is herein provided 60 with an armature in the form of a core K⁵ connected to operate a suitable switch to complete the motor circuit. In the present example, the core K⁵ is connected by a rod K⁶ to a suitable primary switch comprising a 65 contact plate K⁷ which, when the core coil

is energized and the core is lifted, makes contact across a pair of jacks L, and when the coil is de-energized and the core drops, breaks said contact and then makes contact across a pair of jacks K⁹.

The primary switch is connected in turn to operate a suitable secondary switch as follows: The jacks K⁹ and L on one side are connected by branch wires 15 and 16 to the positive line 10. The jack L on the other 70 side is connected by a wire 17 to one terminal of coil I, the other terminal of which is connected by a wire 18 to the negative line 14. The remaining jack K⁹ is connected by a wire 19 to a spring yielding jack 9. The latter is a companion to a spring yielding jack 8, which is connected by wire 20 to one terminal of a coil M, which is a companion to the coil I. The other terminal of the coil M is connected by a wire 21 to the negative 80 line 14.

The companion coils I and M have cores J pivotally connected to a lever K carrying contact making pieces K' and K². The contact making piece K' co-operates with and 90 closes the motor circuit across jacks 6 and 7, one of which is connected to the negative line 14, while the other is connected by a wire 22 to one terminal of the motor B⁴, the other terminal of which is connected to 95 the positive line 10.

When, therefore, the coil K⁴ is energized by the closing of the primary circuit by any one of the contacts 1, 2 and 3, or by the switch D and the coil K⁴ lifts the plate K⁷ 100 into contact with the jacks L, a circuit is completed across the latter to the coil I which is thus energized. This causes the core J to rock the lever K toward the left (Fig. 5), carrying the contact piece K² into 105 contact with the spring yielding jacks 8 and 9, which then yield against springs T. The latter permit the lever K to continue to move to the left after the contact piece K² has come into contact with the jacks 8 and 9, so 110 that, upon further movement of said lever, the contact piece K' brings up against the jacks 6 and 7, thus completing the motor circuit and starting the motor. Incidentally, it will be observed that the yielding springs 115 T yield to permit proper alinement of the contact making piece K'. A spring K³ is arranged to hold the lever to the left after it has been moved as just described.

The motor, having thus been started, will 120 continue in operation until, owing to the de-energizing of the coil K⁴ caused by the breaking of the primary circuit, the contact plate K⁷ again rests on the jacks K⁹. When this occurs, a circuit will be completed across these jacks from the positive line 10 to the wire 19, through the jack 9 contact making piece K², jacks 8, to the wire 20, coil M and wire 21, to the negative line 14. The coil M, having thus been energized, will cause the 130

core J to swing the lever K toward the right, said lever carrying the contact piece K' out of contact with the jacks 6 and 7, thus opening the motor circuit and stopping the 5 motor.

It has been found in practice that a carrier on entering a bend at the foot of a transit tube riser, such as that shown at the right of Fig. 1, and having to overcome the resistance of a contact maker trip such as C', is likely to stop at that point and rest on the trip. This does no harm, however, because if it strikes with sufficient force to operate and go past the trip C', said trip will have 10 made a contact of sufficiently long duration to start the motor, and the circuit controller E will instantly respond to the consequent reduction of pressure in the system and will maintain the previously established circuit. 15 It is evident that this must be so since the carrier, being in the transit tube, whether in motion or not, presents an obstruction, and hence the diminished pressure in the transit tube, being communicated to the controller 20 E, causes the motor to continue in operation until the carrier is discharged. If the carrier, as above stated, should stick in operating the trip C', the spring of the trip would still yield sufficiently to allow the trip to 25 close the circuit, whereupon the pump would start and propel the carrier.

Now it must be evident that the operation of the circuit closers 1, 2 and 3 is only momentary, and simply serves to start the motor 30 and initiate the air current, and that the consequent change of the air pressure in the system will act upon the controller E to keep the motor in operation and to maintain the previously initiated air current. The controller E, however, must be given sufficient time to come into action and, since the switch plate K' would commence to drop the moment the coil K⁴ is deenergized, said switch plate would instantly complete a circuit 35 across the jacks K⁹ and might at once stop the motor, if said switch plate were permitted to drop without restraint. Any suitable means may be provided to retard the descent of the switch plate, but herein I have 40 shown for such purpose a dash pot K⁸, which may be any of the usual types. As illustrated in Fig. 5, the dash pot comprises a piston S working in a cylinder K⁸ and carried up and down therein by the rod K⁶. The piston is 45 provided with holes S' which, when open, permit the free passage of a suitable fluid such as oil, during the ascent of the piston. The descent of the piston, however, is retarded by reason of the closing of the holes 50 S' by a suitable valve, herein a plate S² carried by the rod K⁶, and free to move up and down thereon to a limited extent. The moment the latter commences to drop, the plate 55 S² closes the holes S', whereupon the only 60 means of escape of the oil from the under-

side of the piston is the slow leakage about the sides of the latter and between the plate S² and the piston S, and through the holes S'. It follows that the dash pot imposes a restraint upon downward movement of the 70 switch plate, and thus gives the controller E time to act to maintain the previously established motor circuit by reenergizing the coil K⁴. The latter then prevents the switch plate from descending and contacting with 75 the jacks K⁹, as would otherwise be the case.

In Fig. 5, there is shown the electric circuit controller E with a pipe connection E' to the transit tube B, operating as hereinbefore described in connection with Fig. 1, 80 but it will be understood, however, that an electric circuit controller E' (Fig. 6) might be employed so that the pipe E' would be connected to the sub-atmospheric pressure transit tube B, and the pipe E⁸ to the super- 85 atmospheric pressure transit tube or tubes N.

From the foregoing description of the devices shown in Figs. 4, 5 and 6, it will be clear that a diminution of the pressure in the chamber E¹⁰ of the electric circuit controller E', to a point below that of the atmosphere, or an increase of the pressure in the chamber 9, or both, by an obstruction of any of the transit tubes by reason of a carrier being despatched, will lift the weight 90 E², thus closing the contact D and maintaining the motor circuit. When, however, owing to the discharge of the carriers in transit or by reason of the carrier or carriers outrunning the air current when descending a 100 tube riser, the motor will be continued in operation during the interval of time consumed by the descent of the switch plate K' from the jacks L to the jacks K⁹, and the motor will not stop until the switch plate completes a circuit across the jacks K⁹.

As before stated, any suitable form of electric controller may be employed, instead of the diaphragm types exemplified by the controllers E and E' (Figs. 2, 3 and 6). For 110 example, manometers R (Figs. 8, 9, 10 and 11) may be employed, the column e' being a conducting fluid such as brine or other suitable liquid. Figs. 8 and 9 show as a substitute for the electric circuit controller 115 E' a manometer R connected to the transit tubes N. Fig. 8 indicates, by the difference in height of the levels e² and e³, the pressure in the pipe E⁸, while the blower is still in operation but with no carrier in the tube, 120 while Fig. 9 indicates by the difference in height of the levels e⁴ and e⁵ the pressure in the pipe E⁸, when there is a carrier in transit.

A similar manometer R is illustrated in Figs. 10 and 11 connected with the transit 125 tubes B through pipe E', Fig. 10, showing by the difference of levels e⁶ and e⁷, the pressure below that of the atmosphere when the blower is in operation, but no carrier in the transit tube. Fig. 11 shows by the 130

difference of levels e^8 and e^9 the diminution of pressure to a point below that of the atmosphere when the blower is in operation, and there is a carrier in the transit tube. In 5 these manometers, the differences of height of the fluid are utilized to complete and interrupt the circuit by the use of electrodes f shown in Figs. 8, 9, 10 and 11, which, when connected through the conducting fluid e' as in Figs. 9 and 11, accomplish the same result as when the contacts D of the controllers E and E' are closed. When the levels are as indicated in Figs. 8 and 9, the circuit is opened, just as in the case of the controllers E and E' , the opening of the contact D opens the circuit. 10 15

While I have herein shown and described certain specific embodiments of my invention for illustrative purposes, and have discussed in detail the construction and arrangement incidental to the specific applications thereof, it is to be understood that the invention is limited neither to the mere details or relative arrangements of parts, nor to the specific embodiments herein shown, but that extensive deviations from the illustrated forms or embodiments of the invention may be made, without departing from the principles 20 25 30 thereof.

Having thus described my invention, what I claim and desire by Letters Patent to secure is:—

1. In an apparatus of the character described, a carrier transmission tube, an air-moving device connected thereto, a motor for driving said air-moving device, means for energizing said motor, and motor-controlling means for keeping said motor in 35 operation and controlled by the differential pressure created by a carrier or carriers in transit.

2. In an apparatus of the character described, a carrier transmission tube, an air-moving device connected thereto, a motor for driving said air-moving device, means remote from the despatching inlet of said tube for starting said motor, and motor controlling means for keeping the motor in 45 50 operation and controlled by the differential pressure created by a carrier or carriers in transit.

3. In an apparatus of the character described, a carrier transmission tube provided with stations for sending and receiving carriers, air moving means connected thereto, a motor for driving said air moving means, means for energizing said motor, and motor controlling means controlled 55 60 by the air for continuing the motor in operation due to the continued presence of a carrier or carriers in transit between said stations.

4. In an apparatus of the character described, a carrier transmission tube, an air

moving device, a motor for driving said air moving device, means for energizing said motor, motor controlling means for keeping said motor in operation controlled by the differential pressure due to a carrier in 70 transit, and means for keeping the motor in operation while a carrier is in a portion of the transit tube where the carrier in transit does not act as an obstruction until the carrier again controls said motor or is 75 discharged from said tube.

5. In an apparatus of the character described, a carrier transmission tube, an air moving device, a motor for driving said air moving device, an automatic motor starting, maintaining and stopping device controlled during a portion of its operation by the pressure due to a carrier or carriers in transit, and a retaining device controlling the second mentioned device during another 85 period or periods of the carrier travel when differential pressure due to the carrier in transit is non-existent.

6. In an apparatus of the character described, a carrier transmission tube, an air 90 moving device, a motor for driving said air moving device, means for causing said motor to start, motor controlling means for keeping said motor in operation and controlled by the differential pressure created by a 95 carrier or carriers in transit, and means for causing the restarting of said motor to insure the delivery of a carrier or carriers in transit.

7. In an apparatus of the character described, a carrier transmission tube, an air moving device, a motor for driving said air moving device, means remote from the despatching inlet for causing said motor to start, motor controlling means for keeping 100 105 said motor in operation and controlled by the differential pressure created by a carrier or carriers in transit, and means for causing the restarting of said motor to insure the delivery of a carrier or carriers in transit. 110

8. A carrier transmission apparatus comprising, in combination, a carrier transmission tube, means including an air-propelling device for moving air through said tube, means for causing the initiation of a carrier-propelling air-current in said tube by starting said air propelling device, and means controlled by the differential pressure created by a carrier or carriers in transit to cause the maintenance of the previously 115 initiated air-current by keeping said air-propelling device in operation.

9. A carrier transmission apparatus comprising, in combination, a carrier transmission tube, means including an air-propelling device for moving air through said tube, means for causing the initiation of a carrier-propelling air-current in said tube by starting said air-propelling device, means controlled by the differential pressure 120 125 130

- created by a carrier or carriers in transit to cause the maintenance of the previously initiated air-current by keeping said air-propelling device in operation, and means 5 for retarding the action of the last-mentioned means.
10. A carrier transmission apparatus comprising, in combination, a carrier transmission tube having two terminals one of which 10 is constantly in communication with the atmosphere, an air exhauster connected to the other terminal, a motor for driving said air exhauster, means for starting said motor to cause the initiation of an air flow from the 15 atmosphere into and through said tube and into said exhauster, and means controlled by the differential pressure created by a carrier or carriers in transit to cause the maintenance of the previously initiated air 20 flow.
11. A carrier transmission apparatus comprising, in combination, a carrier transmission tube having two terminals one of which is constantly in communication with the atmosphere, an air exhauster connected to the other terminal, a motor for driving said air exhauster, motor controlling means acting 25 through said motor to cause the initiation of an air flow from the atmosphere into and 30 through said tube and into said exhauster, means controlled by the differential pressure created by a carrier or carriers in transit to cause the maintenance of the previously 35 initiated air flow, and means for opposing a gradually yielding resistance to the restoration of said motor-controlling means to its normal condition.
12. A carrier transmission apparatus comprising, in combination, a carrier transmission tube having two terminals one of which 40 is constantly in communication with the atmosphere, air moving means connected to the other terminal, a motor for driving said air-moving means, motor-controlling means 45 acting through said motor to cause the initiation of a carrier-propelling air flow in said tube, and means controlled by the differential pressure created by a carrier or carriers in transit to cause the maintenance 50 of the previously initiated air flow, the last mentioned means including a pressure responsive element having one face subject to the variations in pressure in said tube.
13. A carrier transmission apparatus comprising, in combination, a carrier transmission tube having two terminals one of which 55 is constantly in communication with the atmosphere, air moving means connected to the other terminal, a motor for driving said air-moving means, motor-controlling means 60 acting through said motor to cause the initiation of a carrier-propelling air flow in said tube, means controlled by the differential pressure created by a carrier or carriers in transit to cause the maintenance of 65
- the previously initiated air flow, the last-mentioned means including a pressure responsive element having one face subject to the variations in pressure in said tube, and electrical means operated by said pressure responsive element.
14. A carrier transmission apparatus comprising, in combination, a normally dead carrier transmission tube, air moving means connected thereto, an electric motor for 75 driving said air moving means, electrical motor-controlling means acting through said motor to cause the initiation of an air flow in said tube, and means controlled by the differential pressure created by a carrier or carriers in transit and acting on said motor-controlling means to cause the maintenance of the previously initiated air flow, the last-mentioned means including a pressure-responsive element subject to variation of pressure in said tube.
15. In an apparatus of the class described, the combination of transit tubing in which there is normally no air flow, an air moving device connected thereto, means to cause the establishment of an air flow in said transit tubing, and controlling means for causing the maintenance of said air flow, said controlling means comprising a device operated by increase rarefaction or compression of the air, or both, due to a carrier or carriers in transit.
16. In an apparatus of the class described, the combination of transit tubing in which there is normally no air flow, an air moving device connected thereto, means to cause the establishment of an air flow in said transit tubing, and controlling means for causing the maintenance of said air flow, said controlling means comprising a device operated by increased rarefaction or compression of the air; or both, due to a carrier or carriers in transit, and means for causing the maintenance of the air flow during such times as the carrier does not act as an obstruction to the air flow.
17. In an apparatus of the class described, the combination of a vacuum transit tube, a pressure transit tube, an air moving device having an inlet connected to said vacuum tube and its outlet connected to said pressure transit tube, means to cause the establishment of an air flow in said tubes, and controlling means for causing the maintenance of said air flow, said controlling means comprising a device operated by increased rarefaction or compression of the air, or both, due to a carrier or carriers in transit.
18. In an apparatus of the class described, the combination of a vacuum transit tube, a pressure transit tube, an air moving device having an inlet connected to said vacuum tube and its outlet connected to said pressure transit tube, means to cause the es- 125

tablishment of an air flow in said tubes, and controlling means for causing the maintenance of said air flow, said controlling means comprising a device operated by increased rarefaction or compression of the air, or both, due to a carrier or carriers in transit, and means for causing the maintenance of the air flow during such times as the carrier does not act as an obstruction to the air flow.

19. In an apparatus of the character described, the combination of a carrier transmission tube normally open to the atmosphere and provided with stations for sending and receiving carriers, air moving means including a motor connected thereto, means for starting said motor thereby to establish an air flow in said transmission tube upon the despatch of a carrier and thereafter automatically to stop said motor disestablish said air flow independently of the carrier or carriers in transit, and controlling means rendered effective by the continued presence of a carrier or carriers in transit between said stations to cause the continued operation of said motor and the continuance of the air flow.

20. In an apparatus of the character described, the combination of a carrier transmission tube normally open to the atmosphere and provided with carrier sending and receiving stations, and in which there is normally no air flow, air moving means connected thereto, means for establishing an air flow in said transmission tube upon the despatch of a carrier and thereafter automatically to disestablish said air flow independently of the carrier or carriers in transit, and controlling means rendered effective by the continued presence of a carrier or carriers in transit between said stations to cause a continuance of the air flow.

21. In an apparatus of the character described, the combination of a carrier transmission tube, air moving means, means including a motor to cause the establishment of an air flow upon the despatch of a carrier and thereafter automatically to cause the disestablishment of the air flow independently of the carrier or carriers in transit, controlling means for causing the maintenance of the air flow by controlling said motor, said controlling means being operated by the differential pressure due to a carrier in transit, and means for delaying the automatic disestablishment of the air flow while a carrier is in a portion of the transit tube

where the carrier does not act as an obstruction until the carrier again controls said maintaining means or is discharged from 60 said tube.

22. In an apparatus of the class described, the combination of a carrier transmission tube, an air moving device, air flow establishing, maintaining and automatic stopping 65 instrumentalities including a motor controlled during a portion of its operation by the pressure due to a carrier or carriers in transit, and a retaining device controlling said motor during another period or periods 70 of the carrier travel when differential pressure due to the carrier in transit is non-existent.

23. In an apparatus of the class described, the combination of a carrier transmission 75 tube in which there is normally no air circulation, an air moving device, means for causing the establishment of an air flow, controlling means for maintaining said air flow, said controlling means being responsive to the differential pressure due to a carrier in transit, and means for causing the re-establishment of said air flow to insure the delivery of a carrier or carriers in transit.

24. In an apparatus of the class described, 85 the combination of a carrier transmission tube, means including a motor for establishing an air flow and having capacity for automatically discontinuing the same upon the lapse of a certain time period, and means 90 controlled by the differential pressure due to a carrier or carriers in transit to continue the operation of said motor to prevent the running of the time period.

25. In an apparatus of the character de- 95 scribed, the combination of a plurality of transmission tubes each provided with stations for sending and receiving carriers, air moving means connected thereto, a motor for driving said air moving means, means 100 for energizing said motor, and a single motor controlling means connected to said tubes for continuing said motor in operation due to the continued presence of a carrier or carriers in transit in any one of said tubes.

105
In testimony whereof I have signed my name to this specification in the presence of two subscribing witnesses, this 24th day of September, A. D. 1914.

J. G. MACLAREN.

Witnesses:

ELSIE MACLAREN,
JOSEPH RISOLI.
